SAFETY MECHANISM FOR COILER BLOCKS

Carl O. Bruestle, Rahway, N. J., assignor to Syncro Machine Company, Rahway, N. J., a corporation of New Jersey

Application March 13, 1942, Serial No. 434,548

12 Claims. (Cl. 242—79)

This invention is concerned with a wire coiling machine having in combination therewith safety mechanism operating automatically under the control of the wire being coiled to prevent the terminal or broken end of a wire being coiled from being a free end which might cause injury and for preventing the uncoiling of the wire on the collar under the same conditions.

In the drawings or otherwise processing of steel wire, and particularly wire of larger sizes, it is necessary to permit the terminal end of the wire to pass out of the die so that it becomes a free end. Under present practice the operator of such machines must be vigilant so as to note when the terminal end approaches the die so that the machine can be stopped before the end passes through it. The completion of the draw is then accomplished by what is termed "jogging," that is the machine is intermittently energized so that the free end of the wire as it leaves the die will not whip about and become a serious source of possible injury to the operator. If the end of the wire is allowed to pass from the die with the machine running at normal speed a very serious and dangerous condition is created by the free end of the wire swinging out from the block and sweeping over a considerable area. Upon consideration it will be apparent that a similar condition results should the wire break at any time during the drawing operation. The danger due to breakage is even more serious since it may occur at any time and when the operator or other workers in the vicinity are not expecting it. In addition when the end of the wire comes out of the die, or the wire breaks, and particularly when drawing high carbon steel rods, there is an exaggerated tendency for the wire to uncoil upon release of the wire. A considerable number of turns tend to unwrap under these conditions which exaggerates the tendency of the free end to whip about.

In accordance with this invention these conditions are eliminated where they occur due to the end of the wire coming out of the die, or due to wire breakage, by means of a mechanism controlled by the wire itself, and if desired, manually controlled for gathering in the free end of the wire to prevent it from swinging through the air and to prevent any considerable amount of uncoiling of the turns on the coiler block.

In addition there are more specific and detailed objects of this invention which will be best appreciated after securing a full understanding of the embodiments of the invention selected for illustrative purposes herein.

This invention resides substantially in the combination, construction, arrangement and relative location of parts, all as will be described in detail below.

- 5 In the accompanying drawings,
 Figure 1 is a top plan view of a coiler block and associated mechanism illustrating the combination of one form of the herein invention therewith;
- 10 Figure 2 is a right hand end elevational view with some parts broken away and others in cross-section of this combination;
- 15 Figure 3 is a detailed broken portionwise view showing this structure in operated position;
- 20 Figure 4 is a broken partly cross-sectional view of another form of the inventive combination which is a preferred practical form thereof;
- 25 Figure 5 is a cross-sectional view of the preferred form taken on the line 5—5 of Figure 4 with some parts broken away;
- 30 Figure 6 is a cross-sectional view with some parts broken away taken on the line 6—6 of Figure 4;
- 35 Figure 7 is an enlarged detail cross-sectional view illustrating a modification of the structure of Figures 4, 5 and 6;
- 40 Figure 8 is a cross-sectional view with many parts broken away of a still further modified form of the invention;
- 45 Figure 9 is a similar view of a modification of the structure of Figure 8; and
- 50 Figures 10 and 11 are vertical cross-sectional and broken plan views of a structure comprising a further modification of either of the structures of Figures 8 and 9.
- 55 Except for modifications necessary to apply the subject matter of this invention thereto the particular form of coiler or bull block employed is of no importance. The coil mechanism illustrated in the various figures exemplifies but one possible form to which the invention herein disclosed may be applied. In the form illustrated it consists of a suitable housing 10 in which is journaled a vertical shaft 12 on which the coiler or bull block 11 is mounted for rotation on a vertical axis. The bull block may be of any suitable construction, and as illustrated, in accordance with usual practice is at the wire receiving portion slightly tapered and is provided with a base flange or skirt 15. As is usual the wire W moves to the bull block tangentially at the fillet between the conical portion and its skirt, as is clear from the figures. As illustrated, the bull block is provided with a series of vertical bars or rods 16 upon which the coil collects as the turns thereof

are forced upwardly by each succeeding turn. Within the housing 10 is a worm wheel 14 secured to the shaft 12 and driven in any suitable manner by a shaft 13 (Figure 1) which extends into the housing 10 and is provided with a worm, not shown, meshing with the worm wheel 14. There is illustrated in the drawings an air cooling system which forms no part of this invention. It comprises a circular casing 17 mounted on the housing 10 and surrounding the bull block at the skirt 15. The casing 17 provides an annular passage 19 to which air in suitable volume is supplied through a connection 18. The housing 17 is constructed so as to have an annular orifice 20 positioned to blow air onto the wire as it is coiled on the bull block at the flange, as will be clear for example from Figure 2.

The skirt 15 is provided with a series of circumferentially spaced apertures in which vertically slidable pins 21 are mounted. The pins are headed at both ends so as to be limited in their vertical movements. The top wall 22 of the housing 10 forms a re-entrant structure, as is clear from Figure 2, to provide a recess in which a flat ring 23 is mounted. This ring is of suitable diameter so as to lie under the lower heads of the pins 21, as is clearly seen from all the figures of this modification. Mounted in the wall 22 are a plurality of fixed sleeves 25 which have longitudinal passages therethrough which are counterbored from the upper end and in which lie the rods 24. The upper ends of the rods are permanently secured to the ring 23. In the counterbores of the sleeves are springs 26 which are under compression when the ring is in the position shown in Figure 2, so as to tend to force the ring upwardly.

At a pair of diametrically disposed points the arms 27 are secured to the ring 23 and extend through passages in the wall 22 so as to project therebelow. These arms are pivotally connected at 28 to the ends of levers 29 which are secured for rotation therewith to a horizontal shaft 30 journaled in the housing 10 and disposed as clearly illustrated in Figure 1. A link 31 is pivotally connected as indicated at 32 to one of the arms 29 and extends downwardly to and is pivotally connected at 33 to a lever 34. The lever 34 is secured to a short shaft 35 journaled in a side wall of the housing and projecting externally thereof so as to receive the pedal lever 36. A latch 31 is secured to the outer face of the housing 10 at a point so as to lock the lever in depressed position, as indicated in Figure 2. A switch 38 provided with an operating arm 39 is mounted on the housing so as to be engaged by the pedal lever 36 when in its raised position.

A suitably shaped pulley 40 is positioned on the outside of the housing 10 so as to lie in the path of the wire W as it moves to the bull block along a tangential path, as is clear from Figure 1. The pulley or guidewheel 40 is rotatably mounted on a supporting structure 41 which is vertically slid-able in the top wall of housing 10, and which is pivotally connected at its lower end to a short lever 42 also secured to the shaft 30.

The operation of this mechanism will now be described in detail. After the initial end of the wire to be drawn has passed through the finishing die of the drawing machine (not shown), or 70 has completed any treatment prior to coiling, that end is attached to the bull block by mechanism not shown but commonly employed to insure the formation of the first few coils. Preliminarily to this stringing up operation the op-

erator will depress bodily lever 36 so that all of the parts are in the position clearly shown in Figure 2. He may, if he so desires, latch the pedal lever in depressed position by means of 5 the latch 37 to leave him free in the stringing up operations. If the end of the wire is secured to the bull block, pedal lever 31 is released and if latched, unlatches. The wire W then engages the pulley 40 and holds it in depressed position. 10 The result is that all of the attached mechanism is held depressed because of the connection of the pulley 40 with the shaft 30. The final result is that the pins 21 are in the position shown in Figure 2. The machine is then put in normal 15 running operation by energization of the power drive attached to shaft 13. At this point it may be noted that it is common to drive such machines by means of electric motors and the switch 38 is intended to be connected into the control circuits of the motor so that when the pedal lever 36 is depressed switch 38 is closed so that the motor is under the control of the main controller. Of course, should switch 38 open the main motor will be de-energized and reference to this function will be made later.

The machine is now running at normal speed and will continue to so operate unless the wire breaks or the terminal end comes out of the die or otherwise becomes free. If the operator is 30 vigilant and sees the approach of the end of the wire he may shut the machine down and cause the wire to pass out of the die by means of the usual "jogging" operation. However, if he does not notice the approach of the end of the wire 35 so that the end comes out of the die or should the wire break the pressure of the wire on the pulley 40 will be relieved. Springs 26 will immediately push the ring 23 upwardly to the position shown in Figure 3, and of course all the connected mechanism will assume corresponding positions. Pins 21 will thereupon be projected above the skirt 15 to form a cage or ring about the lowermost portions of the coil on the bull block, and the free end of the wire will be confined so that it will not have sufficient length to sweep over any considerable area. In mechanism of this type the finishing die is usually closely placed with respect to the bull block so that the free end of the wire is not free long, and if it is prevented from uncoiling from the bull block by the cage 21 it will not have sufficient length to do any serious harm.

At the same time that the pins 21 are projected bodily lever 36 will rise and open switch 38 so that simultaneously with the actuation of the safety mechanism the main drive for the bull block will be shut down. Thus the machine will quickly come to rest, minimizing the chances of injury to the operator. The manner of connecting switch 38 to the motor control circuits to accomplish this object will be at once apparent to anyone skilled in this art.

The modification of Figures 4 to 6 inclusive is electro-magnetically operated. In this arrangement the flange 15 of the bull block 11 is provided with a series of circumferentially spaced and circumferentially extending slots 46 in each of which lies an arm 45 of suitable length. Each of these arms is keyed to a shaft 47 journaled in the base of the bull block and having on its other end a lever 48 which is bifurcated at its free end so as to fit around the pin 49. Each pin 49 is mounted in a support 50 secured to the bottom surface of a ring 51. The ring 51 fits in an annular recess in the base of the bull block and

is held therein by a series of clamp plates 52. The ring 51 is held in the recess loosely enough so that it may move a limited amount circumferentially. As illustrated in Figure 5, a series of lugs 53 are secured to the upper face of the ring 51 and each forms an anchor for one end of a spring 54. The other end of each spring is secured, as indicated at 55, to the bull block. The ring is notched as indicated at 51' in Figure 5, so as to cooperate with a stop pin 51a mounted on the bull block to limit circumferential rotation of the ring. The springs 54 normally hold the ring in the position shown in Figure 5, at which time the various associated parts are in the position shown in Figure 4. As clearly illustrated in Figure 6, a brake arm 56 is pivotally mounted on the housing 10 at 57. A suitable friction shoe like that at 56' in Figure 7 is interposed between the arm 56 and the ring 51. The free end of arm 56 engages a cam 57 mounted on a shaft 58 journaled in the housing 10 (see Figure 4). The shaft 58 projects outside of the housing and has a lever 59 secured on its end. This lever is pivotally connected at 60 to a link 61, which in turn is pivotally connected at 64 to the plunger 65 of a solenoid 62 mounted on the side of the housing. A spring 63 cooperates with the link 61 on a stop as shown so as normally to hold the plunger 65 in raised position and the attached parts in the position shown in Figure 4.

A switch 100 having an operating arm 101 is positioned so as to be engaged by the wire W in its tangential path of approach to the bull block. When the machine is in operation switch 100 is open, the contacts of the switch are connected in an obvious manner to a suitable power source and to the terminal of the solenoid 62, so that it is de-energized when the machine is in normal operation. In the operation of this mechanism the spring is sprung up as before and set in operation at normal speeds, at which time the safety mechanism parts are in the position shown in Figure 4. Should the wire break or the end come out of the die, switch 100 closes, energizing solenoid 62 which attracts its plunger 65 causing shaft 58 to rotate in a counterclockwise direction when viewed from the left hand end (Figure 4). The rotation of shaft 58 through the action of cam 57 causes the brake lever 56 to press the brake shoe against ring 51 which is rotating bodily with the bull block 11. This pressure on the ring 51 retards its movement sufficiently to cause it to shift on the bull block from the position shown in Figure 5 in a clockwise direction until the right hand end of notch 51' engages the pin 51a. This motion is accomplished against resistance of spring 54. This movement of ring 51 causes rotation of shaft 47 through the pins 49 and the arms 45. The result is that the arms 45 rotate from the position shown in Figure 4 to an upstanding position, as illustrated in Figure 6, thereby forming a cage about the coiled portions and preventing the free end of the wire from sweeping over a large area. As before, the main motor drive may be automatically de-energized in any one of many obvious ways to bring the machine to a stop, or if desired it may be brought to a stop by manual de-energization of the drive motor.

The structure illustrated in Figure 7 discloses sufficient of the mechanism to illustrate a further modification. In this case arms corresponding to the arms 45 as illustrated at 46' in Figure 7, are pivotally mounted at 47' in the skirt 15 of the bull block 11. In this case the arms 46' lie

radially of the bull block. As before, a ring 51' is mounted for limited circumferential movement on the bottom of the bull block and is held in place by means of clamp plates 52'. A brake lever 56 operated by the cam 57 on the shaft 58 is employed as before. In this case, however, the outer circumferential edge of the ring 51' is notched as shown at 51b to provide camming surfaces which engage the holes or rear lower ends of the levers 46'. Thus when the brake is applied as before the ring 51' shifts and its camming surfaces cause the levers 46' to rotate to the dotted position shown in Figure 7 to again cage in the adjacent portions of the wire on the block.

Figure 8 shows a modification which employs the operating mechanism of Figures 1 to 3 inclusive. In this case, however, the pins 21 are dispensed with and a cylindrical cage 66 is positioned so as to surround the skirt 15 of the bull block 11. In this case the pins 24 are secured to the cage and the cage is connected by the bars 27 to the arms 29 as before. In this case when the wire breaks or comes out of the die it releases the mechanism so that the cylindrical cage 66 is projected upwardly to the dotted position shown in Figure 8 forming a continuous cage as distinguished from the interrupted or discontinuous cages previously described.

The structure of Figure 9 is like that of Figure 8 in that a cylindrical cage 66 is employed. In this case, however, the cage 66 rotates with the bull block 11 and is attached to the end surface thereof by means of projecting bolts 67 so that the cage may slide on them. This arrangement may be solenoid operated as in the case of the structures of Figures 4, 5 and 6. The link 61 of the solenoid mechanism is connected by an arm 70 secured to the shaft 39 which corresponds to the shaft 39 of Figure 1. A pair of arms 68 are positioned to engage the cage on its end surface at a pair of diametrically opposed points through the agency of rollers 69 on their ends. With this arrangement when the wire breaks or comes out of the die the solenoid is energized so that the arms 68 move to the dotted position and raise the cage 66 to the dotted position path shown in Figure 9.

The arrangement of Figures 10 and 11 may be considered a modification of the arrangement of Figure 9. In this case the cage consists of a ring 66' vertically slidable on the bolts 67 secured to the under surface of the bull block 11. A series of vertical arms 72 are welded to the ring 66' and are positioned so as to be slidable vertically in radial notches on the flange 15, as shown in Figure 11. The ring 66' may be raised by the mechanism illustrated in Figure 9 so that when the wire breaks or the end comes out of the die, the arms 72 will be projected to the dotted position (Figure 7) to form an interrupted cage.

From the above description of the various modifications of this invention it will be apparent that the subject matter thereof is capable of a wide range of physical embodiments. I do not, therefore, desire to be strictly limited to the disclosure which has been given in an illustrative sense, but rather to the scope of the claims granted me.

What is claimed is:

1. In a coiling machine the combination with a rotatable coil forming member, of a plurality of movable arms mounted on said member so as to surround it when moved upwardly, said arms

being normally in retracted position below the coil, means for moving said arms from retracted position to form a cage about the adjacent region of said member, and means positioned to engage the strand for actuating said last means when the strand breaks.

2. In a wire coiling machine the combination with a rotatable coil forming member, of a cylindrical cage mounted adjacent the base of said member and co-axially therewith, said cage being below the path of movement of a strand to said member, means biased to move said cage co-axially to enclose the adjacent portion of said member and means engaged by the strand for restraining said biased means until the strand breaks.

3. In a wire coiling machine the combination with a rotatable coil forming member, of a cylindrical cage movably mounted adjacent the base of said member and co-axially therewith, said cage being below the path of movement of a strand to said member, electro-magnetically actuated means for moving said cage axially towards said member and means engaged by the strand for controlling said last means.

4. In a machine for coiling a strand, the combination with a rotatable member for receiving thereon a strand to form a coil, of means movable to form a cage about said member and the coil thereof, biasing means for moving said movable means to cage formation, and means engaged by the strand for restraining said last means until the strand breaks or runs out.

5. In the combination of claim 4, said movable means comprising a plurality of arms supported around said rotatable member.

6. In a strand coiling machine, the combination with a rotatable member for receiving a strand thereon to form a coil, and cage forming elements positioned concentrically about said member and normally in retracted position, of means operated when the strand breaks or runs out to move said cage forming elements from retracted position to surround the strand receiving end of the rotatable member to limit the unwinding of the coil formed thereon.

7. In a strand coiling machine, the combina-

tion with a rotatable bull block having a skirt at its base, of movable cage forming means supported around said skirt, means for urging said cage forming means upwardly about a coil formed on said bull block, and means engaged by the strand in passing to the bull block for holding said cage forming means in depressed position until the strand breaks or runs out.

5 8. In a strand coiling machine, the combination with a rotatable bull block having a skirt on its base, of means movably supported on the skirt of the bull block for forming a cage about the block in the region of the skirt, means restrained by the strand going to the bull block for moving said cage forming means into cage forming position when released through breakage or running out of the strand.

9. In the combination of claim 8, said cage forming means comprising a plurality of arms pivotally mounted on the skirt of the bull block.

10 10. In a strand coiling machine, the combination with a rotatable bull block, of a plurality of levers pivotally mounted on the bull block and normally lying in a retracted position, means for pivoting said levers to a projected position, and means restrained by the strand going to the bull block for projecting said levers when the strand breaks or runs out.

11. In a coiling machine, the combination with a rotatable coil forming block, of a plurality of arms pivotally mounted on said block in a circular line concentric therewith, and means including a member engaged and controlled by a strand being coiled on said block for actuating said arms to a position to form a cage about the adjacent portion of said block when the strand breaks or runs out, to free said member.

12. In a wire coiling machine, the combination with a rotatable coil forming block having a slotted skirt, of a plurality of cage forming members mounted in said slots in retracted position, and means including a member normally engaging the strand for projecting said members into position to surround the strand receiving portion of said block when the strand breaks or runs out so as to free said member.

CARL O. BRUESTLE.
